MOUNTING FOR JACQUARD CYLINDERS

Herbert V. Foster, Providence, R. I., assignor to Crompton & Knowles Jacquard & Supply Company, Pawtucket, R. I., a corporation of Massachusetts

Application October 9, 1939, Serial No. 298,559

11 Claims. (Cl. 139—317)

This invention relates to improvements in jacquards and more particularly to the mounting for the gudgeons of the jacquard cylinders.

In my prior Patent No. 2,045,946 I show a bearing for the jacquard cylinder gudgeon comprising a sleeve around the gudgeon removable from the latter and cooperating with an anti-friction bearing held in a fixed part of the jacquard structure. It is essential to preserve horizontal alignment of the needle holes in the jacquard cylinder so that they will register correctly with the needles controlling the warp lifting jacks. It is an important object of my present invention to modify the bearing set forth in my aforesaid patent by adding a positioning screw or the like for end adjustment of the cylinder so constructed as to permit lubricating of the interior of the bearing.

It is a further object of my present invention to provide a wear resisting plug between the end of the gudgeon and the adjusting screw so located as to be lubricated when grease or oil is introduced through the adjusting screw. This plug may conveniently be carried by an extension of the sleeve which surrounds the cylinder gudgeon as set forth in the aforesaid patent and is removable so that when worn it can be renewed. The plug prevents direct contact between the adjusting screw and the cylinder gudgeon to prevent wear of the latter, and the lubrication to be described hereinafter also prevents wear of the plug and screw.

With these and other objects in view which will appear as the description proceeds, my invention resides in the combination and arrangement of parts hereinafter described and set forth.

In the accompanying drawing, wherein a convenient embodiment of my invention is set forth, Fig. 1 is a side elevation of a portion of the jacquard incorporating my invention.

Fig. 2 is an end elevation on an enlarged scale looking in the direction of arrow 2, Fig. 1.

Fig. 3 is a detailed vertical section on line 3—3 of Fig. 2, and

Fig. 4 is a detailed longitudinal section through the adjusting screw on line 4—4, Fig. 3.

Referring to the drawing, I have shown the jacquard cylinder 10 having a gudgeon 11 on each end thereof. Horizontal pins 12 at the ends of the cylinders cooperate with positioning hammers 13 urged downwardly by springs 14, one of which is shown in Fig. 3, to assure correct angular position of the cylinder around its

axis when presented to the needles not shown of the jacquard.

The structure at each end of the jacquard is substantially the same as that shown in Fig. 3 and it is thought a description of one end, that is the right end, as shown in Fig. 1 will suffice for both ends.

The gudgeon 11 is surrounded by a sleeve 20 secured to the gudgeon by a collar 21 and set screw 22. The latter extends through the sleeve 10 to hold it against substantial horizontal misplacement along the gudgeon. The sleeve extends into an anti-friction roller bearing R comprising rollers 30 enclosed in a surrounding shell 31 and lying around the hardened sleeve 20. The bearing R has a chamber 33 to receive a lubricant for the rollers 30.

The bearing R is held by set screw 37 carried by a bearing bracket 36. The upper part of the latter is secured to fixed structure 40 by means 20 of a bolt 45, while the vertical position of the bracket is determined by an adjusting screw 42 passing through a threaded arm 44 of the structure 36.

The matter thus far described may be substantially the same as shown in my aforesaid patent with the exception of the sleeve 20 which is modified for a purpose to appear hereinafter. For a further understanding of the structure and operation of those parts of the bearing and associated parts not directly concerned with the subject matter of my present invention reference may be had to the patent mentioned.

My present invention relates more particularly to an end adjustment for the jacquard cylinder 10 and in carrying my invention into effect I provide horizontal adjusting screws 50 and 51 located respectively at the right and left end of the cylinder as viewed in Fig. 1. Each of these screws and the parts associated therewith are substantially the same, and I will describe the invention as applied to the right end of the jacquard with the understanding that it applies to the structure at the left end of the jacquard also.

The screw 50 is threaded into bearing R and is held in its horizontal position with respect to the bearing R by means of a lock nut 52. The previously described set screw 37 determines the horizontal position of the bearing R, hence the screw 50 will be held fixedly in adjusted position by the nut 52. In order that the screw 50 may be turned it is provided with a head 53 accessible from the outer side of the jacquard.

The previously described sleeve 20 is extended 55

as at 55 to overhang the end 56 of the gudgeon 11. Fitted into the overhanging end of the sleeve is a wear resisting plug 60 formed of a wear resisting material, such as bronze, and shown 5 herein as having a head 61 of a diameter somewhat larger than the internal diameter of the sleeve 20 so that it can engage the end of the sleeve. The inner end of the screw 50 bears against the vertical face 62 on the outer part of 10 the plug 60 and it is by this relation that the adjusting force is transmitted longitudinally from the screw 50 to the sleeve 20.

In order that the chamber 33 may be filled 15 with lubricant the screw 50 is provided with a bore 65 closed at its outer end by a fitting 66. The fitting has a bore 70 closed at its inner end by a ball 71 urged against a seat 72 on the interior of the fitting by a spring 73 held in place by a web 74 of the fitting perforated at 75 for 20 passage of grease or the like. Lubricant may be introduced under pressure through the bore 65 against the plug 60, the lubricant being squeezed laterally through the small clearance space between the screw 50 and the plug 60 and into the 25 chamber 33, thus lubricating the plug.

Since sleeve 20 is fastened to the gudgeon 11 by set screw 22, motion of the adjusting screw 50 to the left, for instance as viewed in Fig. 3, will move the cylinder 10 to the left by a force 30 transmitted through the plug 60 and the sleeve 20. While I have shown the particular form of plug in association with the extended end of the sleeve 20 I do not wish necessarily to be limited to that form of plug since it is sufficient if the 35 latter lie between the screw 50 and the gudgeon of the cylinder and preferably though not necessarily is held in position by the sleeve 20.

From the foregoing it will be seen that I have 40 provided simple means for adjusting the position of the jacquard cylinder in the direction of its axis and that this adjustment is effected by means of a screw or the like through which lubricant can be introduced into the chamber 33. It will also be seen that the shell 20 can conveniently be extended to provide means for holding 45 the wear plug 60 in position for engagement with the adjusting screw 50. Also, the fact that the lubricant which is introduced into chamber 33 is squeezed out through the space between the end 50 of the screw 50 and the plug insures proper lubrication of the latter.

Having thus described my invention it will be seen that changes and modifications may be made therein by those skilled in the art without departing from the spirit and scope of the 55 invention and I do not wish to be limited to the details herein disclosed, but what I claim is:

1. In a jacquard having a cylinder provided 60 with a gudgeon extending into a fixed bearing member, an adjusting screw in the bearing member substantially in alignment with the gudgeon and movable within the bearing member toward and from the cylinder, and a body of wear resisting material introduced in force transmitting 65 relationship between the adjusting screw and the cylinder to communicate an adjusting force from the screw to the cylinder.

2. In a jacquard having a cylinder provided 70 with a gudgeon extending into a fixed bearing member, an adjusting screw threaded into the bearing member in alignment with the axis of the cylinder and movable with respect to the bearing member toward and from said cylinder, and a body of wear resisting material in engagement 75 with the end of the screw adjacent to

the cylinder and fixed with respect to the latter to transmit an adjusting force from the screw to the cylinder in the direction of the length of the latter.

3. In a jacquard having a cylinder with a 5 gudgeon extending through a sleeve secured thereto and rotatable within a fixed bearing member, an adjusting screw in the bearing member movable in the direction of the length of the gudgeon, and a wear resisting element between 10 the adjusting screw and the sleeve to transmit an adjusting force from the screw to the sleeve.

4. In a jacquard having a cylinder with a 15 gudgeon extending through a sleeve secured thereto and rotatable within a fixed bearing member, an adjusting screw substantially in alignment with the axis of the gudgeon and threaded into the bearing member for movement toward and from the cylinder, and a wear 20 resisting element between the adjusting screw and the sleeve to transmit a force from the screw to the sleeve to move the cylinder.

5. In a jacquard having a cylinder with a 25 gudgeon extending through a sleeve secured thereto and rotatable within a fixed bearing member, an adjusting screw substantially coaxial with the gudgeon and threaded into the bearing member, and a wear resisting plug held by the sleeve in position for engagement with the screw to transmit a force from the latter to the 30 sleeve to move the cylinder.

6. In a jacquard having a cylinder with a 35 gudgeon extending through a sleeve secured thereto and rotatable within a fixed bearing member, an adjusting screw threaded into the bearing member and movable with respect to the latter in a direction toward and from the cylinder, and a wear resisting plug supported by the sleeve and having a portion thereof in engagement with the end of the sleeve adjacent 40 to the adjusting screw to transmit an adjusting force from the adjusting screw to the sleeve to move the cylinder.

7. In a jacquard having a cylinder provided 45 with a gudgeon extending into a fixed bearing member having a lubricating chamber therein, a screw threaded into the bearing member and extended into the lubricating chamber and having a bore therein through which lubricant may 50 be introduced into the chamber, and a body of 55 wear resisting material fixed with respect to the cylinder in position to transmit an adjusting force from the screw to the cylinder in the direction of the length of the latter and positioned to be lubricated by lubricant introduced through said adjusting screw.

8. In a jacquard having a cylinder provided 60 with a gudgeon extending into a fixed bearing member having a lubricating chamber thereon, an adjusting screw threaded into the bearing 65 member coaxially with the gudgeon and having a bore therethrough for introduction of a lubricant into the lubricating chamber, and a body of wear resisting material engaging the screw and fixed with respect to the cylinder and having that 70 part thereof which engages the screw in position to be lubricated by lubricant introduced through the adjusting screw, said plug transmitting an adjusting force from the adjusting screw to the cylinder in the direction of the length of the latter to move the cylinder.

9. In a jacquard having a cylinder provided 75 with a gudgeon extending into a fixed bearing member having a lubricating chamber therein, a screw threaded into the bearing member and 80

movable toward and from the cylinder with respect to the bearing member and having a bore therein through which lubricant may be introduced into the lubricating chamber, and a body of wear resisting material rotating with the cylinder and fixed longitudinally with respect to the cylinder and extending across that end of the bore in the adjusting screw from which lubricant emerges, said body to transmit an adjusting force from the adjusting screw to the cylinder in the direction of the length of the latter and being lubricated by lubricant passing from the bore into the lubricating chamber.

10. In a jacquard having a cylinder with a gudgeon extending through a sleeve secured thereto and rotatable within a fixed bearing member having a lubricating chamber therein, an adjusting screw threaded into the bearing member and extending into the lubricating chamber and having a bore therethrough for introduction of a lubricant into the chamber, and a wear resisting element between the adjusting screw and the sleeve having engagement

with the end of the adjusting screw to transmit an adjusting force from the screw to the sleeve to move the cylinder and being in position to be lubricated by lubricant emerging from the bore.

11. In a jacquard having a cylinder with a gudgeon extending through a sleeve secured thereto and rotatable within a fixed bearing member having a lubricating chamber therein, an adjusting screw threaded into the bearing member coaxially with the gudgeon and extending into the lubricating chamber, a body of wear resisting material between the adjusting screw and the sleeve to transmit an adjusting force from the screw to the sleeve in the direction of the length of the gudgeon to move the cylinder, 15 said adjusting screw having a bore therein through which lubricant can be introduced into the lubricating chamber and against said body of wear resisting material adjacent to the point of contact between the adjusting screw and the 20 said body.
